[57] CLAIM

The ornamental design for a diamond gauge, as shown and described.

DESCRIPTION

FIG. 1 is a top plan view of a diamond gauge showing my new design, the bottom being a mirror image thereto;

FIG. 2 is a typical side elevational view thereof;

FIG. 3 is a cross-sectional view thereof as taken from line 3—3 of FIG. 1.

FIG. 2 - FIG. 3 -

FIG. 1 -
